UNITED STATES PATENT OFFICE

GEORGE CROSSLAND, OF WALLINGFORD, VERMONT, ASSIGNEE TO MOHAWK CARPET MILLS, INC., OF AMSTERDAM, NEW YORK, A CORPORATION OF NEW YORK

AXMINSTER SETTING FRAME

Application filed April 5, 1928. Serial No. 267,684.

This invention relates to pattern setting machines employed in winding yarns or threads of different colors according to a pattern upon a loom spool preparatory to the 5 use of such filled spools for weaving therefrom the desired Axminster carpets or rugs.

In winding the yarn of different colors upon a loom spool it is customary to provide a plurality of non-driven rollers spaced circumferentially about the loom spool which 10 contact the peripheral surfaces of the spool, and are rotated by said spool. The rollers comprise an upper roller and a pair of lower rollers, the said rollers being capable of being 15 moved in opposite directions by the yarn being wound on the spool as the winding operation progresses. The upper roller is connected to a suitable mechanism including a weighted member which enables the said 20 roller to be moved upwardly to a limited degree, while the pair of lower rollers are also connected to a separate mechanism including a weighted member which permits these rollers 25 to be moved downwardly within certain limits. The separate mechanisms are designed to cause the rollers to exert a compressive force upon the peripheral surfaces of the 30 spool, and also to counteract the force exerted upon the spool. With the setting frames embodying such mechanism, the maximum length of each yarn or thread that it has been 35 possible to wind on the spool is 23 feet.

In the setting frame of the present invention 40 a plurality of pressure applying members spaced circumferentially about the spool are provided which contact with the peripheral surfaces of the spool and exert a uniform compressive force upon the surfaces of said 45 spool, such compressive force being maintained substantially uniform as the diameter of the spool increases as the winding operation progresses. The pressure applying members are arranged so that one of the members 50 is above the spool and a pair of said members are beneath the spool. The operation of such pressure applying members is controlled by a single mechanism which causes the upper pressure applying member to exert a downward 55 pull upon the loom spool and the pair of

lower pressure applying members, an upward force against the loom spool. This mechanism also enables the upper pressure applying member and the pair of lower pressure applying members to be moved uniformly upwardly and downwardly respectively under the force exerted upon each of said pressure applying members by the yarn being wound upon the spool, and still maintain such members in peripheral contact with said spool 60 during the entire winding operation. By this mechanism it is possible to wind 60% to 70% more yarn upon the spool than is possible with the setting frames as now proposed. With the old setting frames it is possible to wind on the spool yarns or threads of a length of only about 23 feet whereas the yarn spools which have been filled with yarn in the setting frame in accordance with this invention contain yarn the length of which is about 40 feet, 65 the filled spool in both cases being of the same diameter.

Accordingly, one object of this invention is the production of a filled loom spool containing a greater length of threads or yarns than 70 obtained with the prior practice, say for example, 40 feet.

Another object of this invention resides in the provision of a mechanism for causing the pressure applying members to exert a substantially uniform force upon the peripheral surfaces of the loom spool throughout the 75 entire winding operation.

Another object of this invention resides in the provision of a single mechanism which 80 enables the upper pressure applying member and the pair of lower pressure applying members to be moved uniformly upwardly and downwardly respectively under the force exerted thereon by the yarn being wound 85 upon the spool, and still maintain such members in peripheral contact with said spool during the entire winding operation.

A further object of this invention resides in the provision of a mechanism for moving 90 the upper pressure applying member out of contact with the loom spool and simultaneously causing the lower pair of pressure applying members to recede from said spool.

A further object of this invention resides 100

in the provision of a mechanism for rotating the loom spool and stopping the rotation thereof after the spool has made a predetermined number of revolutions.

A still further object of this invention resides in the provision of a stop motion drive mechanism operable by one of the shafts for rotating the loom spool.

A still further object of this invention resides in the provision of a pair of shafts provided with clutching members, and a loom spool having flanged ends adapted to interfit said clutching members.

Still another object of this invention resides in the provision of a mechanism for 15 latching and unlatching the spool when in clutching engagement with the rotatable shafts.

Further objects and advantages of the invention will be apparent from the following 20 description taken in conjunction with the accompanying drawings, in which,

Figure 1 is a front elevation of a setting frame embodying this invention.

Figure 2 is an elevation of one end of the 25 frame.

Figure 3 is an elevation of the other end of the frame.

Figure 4 is a sectional elevation taken on the line 4—4 of Figure 1.

30 Figure 5 is a plan view taken on the line 5—5 of Figure 1.

Figure 6 is a sectional view showing the pressure applying members and associated mechanism in a different position from that 35 shown in Figure 4.

Figure 7 is a sectional elevation taken on the line 7—7 of Figure 2 with the rolls removed.

Figure 8 is a detail view of the stop motion 40 disk.

Figure 9 is an end view of the spool.

Figure 10 is an end view of the spindle.

Figure 11 is a modification of the pressure 45 applying members which contact with the spool during the winding operation.

Figure 12 is another modification of the pressure applying members which contact with the spool during the winding operation.

Referring to the drawings, the illustrative 50 machine shown therein as embodying the invention comprises side frames 1, 1, the tops of which are so constructed as to form supports in which the shafts 5 and 6 are mounted for driving the spool 7 preferably made of metal. The ends of the spool 7 are provided with cupped ends 8 and 9, preferably made of metal, having projections or lugs 10 and 11, the lug 10 being diametrically opposite to the lug 11. One end of each of the shafts 5 and 6 is provided with a disk 12 and 13 respectively. Each of the disks 12 and 13 is provided with a cross-wise slot 14, the said slots being adapted to receive the lugs 10 and 11 of the cupped ends 8 and 9, and clutch 65 the cupped ends 8 and 9 to the shafts 5 and 6,

so that rotation of the shafts is transmitted to the spool.

Shaft 6 is driven by the gear 16 fast thereon, said gear in turn being driven by a larger gear 17 mounted upon a shaft 18. Gear 17 is driven by a pinion 19 mounted upon a shaft 20. The shaft 20 is in turn driven by the large sprocket wheel 21 through the medium of the chain 22 and sprocket 23 carried by the shaft 24. The shaft 24 is in turn driven by clutch disk 25 mounted thereon engaging the clutch member 26 carried by the shaft 27. Motion is imparted to shaft 27 through the medium of gear 28 mounted thereon being in operative engagement with gear 29 carried by the motor shaft 30 of the 80 motor 31.

Upon the shaft 5 is mounted a gear 115 which meshes with a larger gear 116 carried by a shaft 117. The gear 116 meshes with a pinion 118 carried by the shaft 20. Motion is imparted to the shaft 20 from the motor shaft 30 of the motor 31 through the medium of the mechanism above described in connection with the shaft 6.

It will be apparent from the mechanism thus described that when the clutch disk 25 is in clutching engagement with the clutch member 26 motion will be imparted to the shaft 20 from the drive shaft 27, which shaft 20 will in turn drive the train of gears, and thus rotate the shafts 5 and 6 and the spool 7.

The driven clutch disk 25 is adapted to be clutched to and unclutched from the drive clutch member 26 carried by the shaft 27 by the following mechanism. The driven clutch disk 25 carries a collar 32 having pins 34 which are embraced by the yoke 35. The yoke 35 is pivotally mounted on the shaft 36 supported in the brackets 37 carried by the side frame 1 of the machine. Pivotally mounted upon the shaft 36 is one end of a lever 39, the other end of which is provided with a longitudinally recessed portion 40 embracing the pin 41 carried by one end of the bell crank lever 42 pivotally mounted on the pin 43 supported in a bracket 38 secured to the side piece 1 of the machine. The bell crank lever 42 is in turn connected to the rod 45 having a threaded end 46, by the pin 44. Secured to the crank lever 42 and the side frame 1 is a spring 47, such spring being provided for holding the driven clutch disk 25 in inoperative position.

The threaded end 46 of the rod 45 extends through the guide 48 and is adjustably secured thereto through the medium of the nuts 49 and 50. The guide 48 is pivotally connected to the bell crank lever 53 as at 52. The bell crank lever 53 is pivotally secured to the side frame 1 of the machine as at 54. The other end of the bell crank 53 is secured to the pin 56 which pin also has secured thereto one end of the lever 57. The opposite end of the lever 57 is connected by the pin 58 to one

end of the treadle lever 59 which is secured to one end of a rock shaft 61 carried in brackets 60 secured to the side frame 1. The treadle lever 59 is provided with a treadle 3.

5 It will be observed that the mechanism thus described will cause the clutching of the driven clutch disk 25 to the drive clutch member 26 by the operator placing his foot upon the treadle 3, and depressing such treadle. In order to retain the driven clutch disk 25 in clutching engagement with the drive clutch member 26, a latching device is provided. Such latching device comprises a latch member 160 which is fulcrumed as at 162 in a bracket 161 secured to the side frame 1. One end of the latch member 160 is provided with a cut out or notched portion 163 which is adapted to engage the squared end 163¹ of the bell crank 53. The latch member 160 is connected to an arm 164 fixedly secured to a shaft 166 supported in brackets 165 by a rod 167. The end of rod 167 which is secured to the arm 164 is threaded and is adjustably secured to the guide 168 through the medium of nuts 169 and 170. The guide 168 is provided with a boss 171 having an opening therethrough for the reception of the pin 172 which connects the arm 164 to the guide 169. The arm 164 is provided with spaced openings 173 for lengthening or shortening the throw of said arm. Fixedly mounted upon the shaft 166 is a hand lever 174 which is connected to one end of a rocking arm 137 pivotally mounted upon a pin 135 by a cord or chain 139, (Fig. 3). 35 Mounted upon the pin 135 and secured thereto is a lever 132 having at one end thereof a lug 131 which is adapted to ride upon the periphery of a stop motion disk 129 and to seat in the notch 130 therein to stop the rotation of the spool shafts 5 and 6. A weight 136 is secured to the opposite end of the lever 132 by means of a link 138.

A stop motion drive mechanism is also provided for stopping the rotation of the spool shafts 5 and 6, after they have made a predetermined number of revolutions. This stop drive mechanism comprises a worm 123 journaled upon the outer end of shaft 5 which meshes with a worm gear 124 carried by a shaft 125. Mounted upon the shaft 125 is a gear 126 which meshes with a gear 226 carried by a shaft 227 mounted in the longitudinal slots 228 of the bracket 229. The gear 226 meshes with a larger gear 127 carried by a shaft 128 also mounted in bracket 229. Journaled upon the shaft 128 and mounted thereon so as to rotate with the gear 127 is a stop motion disk 129 provided with a notch 130. The lug 131 of the lever 132 is adapted to ride about the periphery of the stop motion disk 129 and seat in the notch 130 under the influence of weight 136 to stop the machine as pointed out above. The ratio of gears 126, 226, and 127 may be changed so as to vary the speed of the stop motion disk 129. Such mech-

anism is particularly advantageous in that it determines the time interval within which the spool 7 is permitted to rotate without varying or changing the speed of the rotation of the spool shafts 5 and 6. The ratio of the gears 126, 226 and 127 is so fixed that by the time the lug 131 has traversed the entire periphery of the disk 129 and has entered into the notch 130 the winding of the yarn upon the spool 7 is completed.

The seating of the lug 131 in the notch 130 of the stop motion disk 129 causes the pin 135 to rotate and in turn actuate the rocking arm 137, the movement of said arm exerting a pull upon the hand lever 174 through the cord 139. This pull upon the hand lever 174 is in turn transmitted to the arm 164 and rod 167 carrying the latch member 160 to move the notched portion 163 of said latch member out of engagement with the squared end 163¹ of the bell crank lever 53, and thereby permit the driven clutch disk 25 to disengage from the driven clutch member 26 and return to inoperative position under the action of the spring 47.

It is to be noted that the hand lever 174 is provided to permit the operator to stop the machine at any time during the winding operation, and also to enable the operator to release the lug 131 from the notch 130 of the stop motion disk 129.

In order that the threads may be wound tightly upon the spool this invention provides an upper pressure applying member or roller 80 and a pair of lower pressure applying members or rollers 81 and 82 which extend parallel to the spool 7 and which are yieldingly supported in a manner to exert pressure against the threads being wound upon the spool as the body of threads being wound thereon increases in diameter.

The upper pressure roller 80 has its ends journaled in a pair of arms 103, one end of which is provided with a notched portion 104. Depending from the arms 103 are extensions 105 provided with arcuate slots 106 which embrace pins 107 carried by the levers 108 mounted upon a rock shaft 109. The other end of the levers 108 are secured to the arms 103 as at 66. The mechanism for operating the rock shaft 109 in order to move the upper pressure roller 80 from the position shown in Fig. 4 to the position shown in Fig. 6 will be hereinafter described.

The arcuate slots 106 are provided for the purpose of permitting the arms 103 supporting the pressure roller 80 to be moved upwardly about the point 66 as a pivot as the diameter of the yarn being wound upon the spool 7 increases. Such slots also act to limit or restrict the downward movement of the arms 103 supporting the pressure roller 80 when said roller is moved away from the spool or to the position shown in Fig. 6.

Suitably supported in connectors 112 are

levers 110 having their upper ends turned inwardly so as to form detents or hooks 111, the said detents or hooks being adapted to engage the notched portions 104 of the arms 103. The connectors 112 are in turn adjustably secured to levers 71 by pins 68 held in longitudinal slots 69 of said levers. The levers 71 are journaled upon the shaft 64 supported in the side pieces 1, 1 of the machine. The ends of the levers 71 adjacent the shaft 64 are connected together by means of a shaft 95. The opposite ends of the levers 71 are connected together by a bar 76 upon which are mounted a plurality of weights 77 interposed between weights 78 and 79.

The lower pressure rollers 81 and 82 have their ends journaled in the upper ends of rods 90 and 91. The rods 90 and 91 extend through guides 92 and 93 attached to the inside faces of the side plates 1. The lower ends of the rods 90 and 91 are threaded and are adjustably secured in the casting 96 by means of nuts 97, and 98. The casting 96 has a boss or projection 62 which is connected to the shaft 95 by means of a link 63.

The mounting of the upper pressure roller 80 and the pair of lower pressure rollers 81 and 82 with respect to the spool 7 is such that the point about which the upper pressure roller 80 rotates when in operative engagement with the spool 7 is not equidistant from the respective points about which the pair of lower pressure rollers 81 and 82 rotate as is obvious by inspection of Fig. 4. Such mounting of the upper pressure roller 80 is highly important as it results in the peripheral surface of the upper pressure roller 80 engaging the yarn being fed to the spool at a point below the upper peripheral surface of the spool mounted in the machine prior to the winding of the yarn thereon, and thereby causes the yarn to be uniformly wound upon the spool.

It is to be noted that the shaft 64 acts as the fulcrum for the levers 71, and that the levers 110 controlling the upper pressure roller 80 and the rods 90 and 91, casting 96, link 63, and shaft 95 controlling the lower pressure rollers 81 and 82 are connected to the levers 71 on opposite sides of the fulcrum or shaft 64. Also, the levers 110 controlling the upper pressure roller 80 which are longer than the rods 90 and 91 controlling the lower pressure rollers 81 and 82 are secured to the levers 71 at a point between the fulcrum or shaft 64 and the weights 77, 78 and 79 supported by the ends of the levers 71 while the rods 90 and 91 are connected to the levers 71 on the opposite side of the fulcrum or shaft 64. This arrangement of the different means for controlling the upper pressure roller and lower pressure rollers with respect to the weights supported by the ends of the levers enables the upper pressure roller 80 and the pair of lower pressure rollers 81 and 82 to

exert a substantially constant pressure upon the spool 7 as the levers 71 move from the full line position shown in Fig. 4 to the dotted line position shown in such figure as the diameter of the yarn being wound on the spool increases.

It will be apparent from the mechanism thus described that the upper pressure roller 80 is yieldably supported with respect to the spool 7 and as the thread being wound thereon increases in diameter it is capable of being moved by the force exerted thereon by the body of the threads being wound on the spool, and still be maintained in intimate contact with the spool 7 through the action of the weights 77, 78, and 79 exerted through the levers 71 and lever 110, and rods 90 and 91.

The pair of lower pressure rollers 81 and 82 are also capable of being moved by the body of threads being wound on the spool, and yet be retained in intimate contact with the spool 7 through the action of the weights 77, 78 and 79 exerted through link 63, casting 96, and rods 90 and 91. In the form shown in Fig. 11, the upper pressure roller 80 is replaced by a plate 220. In the form shown in Fig. 12, the lower pressure rollers 81 and 82 are replaced by plates 221 and 224.

After the winding of the yarn upon the spool 7 has been completed the upper pressure roller 80 is moved away from the spool 7, the position shown in Fig. 4 to the position shown in Fig. 6 by a novel mechanism which will now be described. Such mechanism also includes means for simultaneously lowering the pair of lower pressure rollers 81 and 82.

As described above the arms 103 in which are journaled the ends of the upper pressure roller 80 are pivoted to the levers 108 as at 66, which levers are in turn mounted upon the rock shaft 109. Carried by the rock shaft 109 is an arm 140 which in turn is connected to a rod 141 as at 142. The rod 141 is adjustably connected to a guide 143 which guide is in turn connected to the arm 144 pivotally supported in a bracket 146 secured to the frame piece 1 of the machine by means of a pin 145. To the pin 145 is secured one end of chain 147 which rides over an idler roller 148 supported in a bracket 149 and carries a weight 150. Secured to and carried by the arm 144 is an idler roller 151 which rides in the slot 152 of the cam 153 mounted on a shaft 154.

As pointed out above the levers 110 having their upper ends turned inwardly so as to form detents or hooks 111 which detents or hooks engage the notched portions 104 of the arms 103 are supported in connectors 112. The connectors 112 are in turn adjustably secured to levers 71 by pins 68 held in slots 69 of said levers. The levers 71 are also provided with slots 73 in which are supported rollers 74 adapted to ride upon the periphery of cams 75 by the shaft 154.

Mounted upon the cam shaft 154 is a

5 sprocket wheel 183 which is connected to a sprocket 186 mounted upon a stub shaft 185 supported in a bracket 189 of the side frame 1 by means of sprocket chain 184. Carried by the stub shaft 185 is a gear wheel 181 which meshes with a gear 180 mounted upon a stub shaft 187 supported in a bracket 188 secured to the side frame 1. Keyed upon the outer end of the stub shaft 187 is a crank handle 10 182.

10 By the operator turning the crank handle 182 motion is imparted to the cam shaft 154 through the gears 180, 181, sprocket wheel 186, sprocket chain 184, and sprocket wheel 183. The rotation of the cam shaft 154 causes the rollers 74 supported in the longitudinal slots 73 of the levers 71 to ride about the periphery of the cams 75 carried by said shaft 154. The riding of the rollers 74 upon the periphery of the cams 75 causes the weighted lever 71 to be raised thus lowering the pair 15 of lower pressure rollers 81 and 82.

15 The rotation of the cam shaft 154 also causes the roller 151 carried by the arm 144 to ride in the slot 152 of the cam 153. The riding of the roller 151 in the slot 152 of the cam 153 exerts a pull upon the rod 141 which is transmitted in turn to arm 140 and rock shaft 109 to rock the said shaft and thus move the 20 upper pressure roller 80 to the position shown in Fig. 6.

25 In order to restore the upper pressure roller 80 and pair of lower pressure rollers 81 and 82 to the position shown in Fig. 4, the operator turns the crank handle in the reverse direction.

30 The mechanism for releasably latching the spool 7 upon the shafts 5 and 6 will now be described. Such mechanism comprises a bracket 190 secured to the side plate 1 of the machine to which is pivotally secured a lever 192 as at 191. The lever 192 is provided with a circular opening which receives the collar 242 fixedly secured to the reduced portion 241 35 of the spindle shaft 6 through the medium of set screws 243. The other end of the lever 192 is provided with a slot or opening 194 in which is supported one end of a hand rod 195. The other end of the hand rod 195 is supported in a standard 196 secured to the opposite side plate 1 of the machine. The end of the hand rod 195 which is supported within the opening 194 of the lever 192 is tapered and is provided with a projection 197 which is 40 adapted to bear against the exterior surface of the lever 192. The opposite end of the hand rod 195 is provided with a square reduced portion 200 which is supported in the standard 196 secured to the opposite side frame 1 of the machine. Surrounding the outer end of the square portion 200 of the hand rod 195 and interposed between the exterior surface of the lever 196 and the washer 198 is a spring 199.

45 When it is desired to remove the spool 7

from the shafts 5 and 6, the operator places his hand upon the hand rod 195, pushes the said rod upwardly until the projection 197 is moved out of engagement with the exterior surface of the lever 192 when the end of the hand rod 195 will be pulled through the opening 194 by the action of the spring 199. The operator then pulls the lever 192 in an outwardly direction thereby causing the slotted disk 13 of the shaft 6 to be moved out of engagement with the projections 10 and 11 carried by the cupped end 9 of the spool 7. The operator then lifts the end of the spool 7 which has been freed from engagement with the shaft 6 and pulls the spool outwardly so as 50 to de-clutch the cupped ends 8 from the slotted disk 12 of the shaft 5.

55 It will be obvious that many changes and alterations may be made in the structure above described without departing from the spirit of this invention, and such modifications are within the intent of the appended claims.

Having thus described the invention, what is claimed as new and desired to be secured by Letters Patent is set out in the appended claims:

1. In a pattern setting machine, the combination of a supporting frame, rotatable shafts mounted in said supporting frame, one of said shafts being movably mounted in said frame, and a latching mechanism for releasably latching said shaft in operative position or moving said shaft to inoperative position and retaining same in said last-named position, said mechanism comprising a lever member pivotally supported in said frame secured to the end of said shaft and having a slot in one end thereof and a hand rod provided with a projection adapted to engage the exterior surface of said lever member when the rod is in operative position and to pass within said slot when said rod is in inoperative position. 95

2. In a pattern setting machine, the combination of a supporting frame, rotatable shafts mounted in said supporting frame, one of said shafts being movably mounted in said frame, and a latching mechanism for releasably latching said shaft in operative position or moving said shaft to inoperative position and retaining same in said last named position, said mechanism comprising a standard member secured to one side of said frame, a hand rod supported in said standard member and having at one end thereof a projection, and a lever member pivotally supported to the opposite side of said frame secured to the end of said movable shaft and having a slot 110 in the end thereof through which the end of said shaft extends, the projection on said hand rod engaging the exterior surface of said lever member secured to said movable shaft 115 when the last named shaft is in operative position. 120

- tion, and passing through said slot when the movable shaft is in inoperative position.
3. In a pattern setting machine, a releasable latching mechanism comprising a standard member projecting upwardly from one side of said machine, a lever member projecting upwardly from the other side of the machine, a hand rod operatively supported in the upper ends of said members and cooperating with said lever member, and means actuated by said lever member for clutching a spool in said machine.
4. In a pattern setting machine, a releasable latching mechanism comprising a standard member projecting upwardly from one side of said machine, a lever member projecting upwardly from the other side of the machine, a hand rod having a projection thereon operatively supported in the upper ends of said members, said projection cooperating with said lever member to hold same in latched position, and means actuated by said lever member for clutching a spool in said machine.
5. In a pattern setting machine, a releasable latching mechanism comprising a standard member projecting upwardly from one side of said machine, a lever member projecting upwardly from the other side of the machine, a hand rod provided with a projection at one end thereof operatively supported in the upper ends of said members, said projection cooperating with said lever member to hold same in latched position, resilient means carried by the other end of said hand rod for moving the rod out of operative engagement with said lever member, and means actuated by said lever member for clutching a spool in said machine.
6. In a pattern setting machine, a releasable latching mechanism comprising a standard member projecting upwardly from one side of said machine, a hand rod provided with a projection having one end thereof supported in the upper end of said standard member, resilient means interposed between said end of said hand rod and said standard member, and a lever member having a slot in the end thereof projecting upwardly on the opposite side of the machine supporting the other end of said hand rod, and means actuated by said lever member for clutching a spool in said machine, the projection being adapted to engage the exterior surface of said lever member when the latching mechanism is in latching position, and to pass through the slot of said lever member when the latching mechanism is in inoperative position.
7. In a pattern setting machine, the combination of a supporting frame, rotatable shafts mounted in said supporting frame, a loom spool adapted to be clutched to said shafts, means for rotating said shafts, and a stop mechanism actuated by one of said shafts for stopping said means when said shafts have made a predetermined number of revolutions.
8. In a pattern setting machine, the combination of a supporting frame, rotatable shafts mounted in said supporting frame, a loom spool adapted to be clutched to said shafts, means for rotating said shafts, and a stop mechanism actuated by one of said shafts for stopping said means when said shafts have made a predetermined number of revolutions, said mechanism comprising a disk provided with a peripheral notch, a clutch mechanism, a releasable device to hold said clutch mechanism in driving engagement, and means to release said device including a member adapted to ride about the periphery of said disk and seat in said notch.
9. In a pattern setting machine, the combination of a supporting frame, rotatable shafts mounted in said supporting frame, a loom spool adapted to be clutched to said shafts, means for rotating said shafts comprising a main shaft, a drive clutch mounted on said main shaft, a driven clutch adapted to drive said rotatable shafts, means for moving said driven clutch into clutching engagement with said drive clutch, a stop mechanism actuated by one of said shafts for disengaging the driven clutch from the drive clutch after said rotatable shafts have made a predetermined number of revolutions including a disk having a peripheral notch, and a releasable device for holding said driven clutch in driving engagement with said drive clutch, said device comprising a lever having a lug, the lug of the lever of said releasable device being adapted to ride about the periphery of said disk and seat in said notch to actuate the said lever thereby by withdrawing said releasable device from engagement with said driven clutch.
10. In a pattern setting machine, means to detachably support and rotate a spool, a plurality of pressure applying members, spaced circumferentially around said spool and contacting the periphery thereof, and a single means for urging one of said members in one direction and another of said members in an opposite direction against the peripheral surface of said spool.
11. In a pattern setting machine, means to detachably support and rotate a spool, a plurality of pressure applying members spaced circumferentially around said spool and contacting the periphery thereof, and a single means for urging two of said members in one direction and another of said members in an opposite direction against the peripheral surface of said spool.
12. In a pattern setting machine, means to detachably support and rotate a spool, a plurality of pressure applying members spaced circumferentially around said spool and contacting the periphery thereof, and

5 a common means for urging two of said members upwardly and another of said members downwardly against the peripheral surface of said spool, said means including a lever and a weight, the upwardly acting members and the downwardly acting member being connected to said lever at opposite sides of the fulcrum thereof.

10 13. In a pattern setting machine, means to detachably support and rotate a spool, a plurality of pressure applying members spaced circumferentially around said spool and contacting the periphery thereof, and a common means for urging two of said members upwardly and another of said members downwardly against the peripheral surface of said spool, said means including a lever, a weight, and mechanism connecting the two upwardly acting members to said lever on one side of its fulcrum, and the downwardly acting member to said lever on the other side of the fulcrum.

15 14. In a pattern setting machine as set out in claim 10 wherein the pressure applying members are non-driven.

20 15. In a pattern setting machine as set out in claim 10 wherein one of the pressure applying members is a plate.

25 16. In a pattern setting machine, means to detachably support and rotate a spool, means to guide a plurality of threads to said spool to be wound thereon, a pressure applying member with yielding means to support it over and in contact with said spool, a pair of pressure applying members with means to support them yieldingly under and in operative contact with said spool, and a single means to adjust the yielding pressure of the upper and lower pressure applying members on the spool as it is being wound.

30 17. In a pattern setting machine, means to detachably support and rotate a spool, means to guide a plurality of threads to said spool to be wound thereon, a pressure applying member with yielding means to support it over and in contact with said spool, a pair of pressure applying members with means to support them yieldingly under and in operative contact with said spool, and a single means to adjust the yielding pressure of the upper and lower pressure applying members on the spool as it is being wound, said single means including a lever, a weight, and mechanism connecting the yielding support means of the upper pressure member to the lever on one side of its fulcrum, and the yielding support means of the lower pressure members to said lever on the other side of the fulcrum.

35 18. In a pattern setting machine as set out in claim 17 wherein one of the pressure applying members is a plate.

40 19. In a pattern setting machine, means to detachably support and rotate a spool, means to guide a plurality of threads to said spool to be wound thereon, a pressure applying member with yielding means to support it over and in contact with said spool, a pair of pressure applying members with means to support them yieldingly under and in operative contact with said spool, and a single means to adjust the yielding pressure of the upper and lower pressure applying members on the spool as it is being wound, said single means including a lever and a weight, the upwardly acting members and the downwardly acting member being connected to said lever at opposite sides of the fulcrum thereof.

ing member with yielding means to support it over and in contact with said spool, a pair of pressure applying members with means to support them yieldingly under and in operative contact with said spool, a single means including a lever and a weight to adjust the yielding pressure of the upper and lower pressure applying members on the spool as it is being wound, and means to shift each of said pressure applying members to inoperative position to permit access to or the removal of the spool.

20 25 30 35 40 45 50 55 60 65 70 75 80 85 90 95 100 105 110 115 120 125 130

20. In a pattern setting machine, means to detachably support and rotate a spool, means to guide a plurality of threads to said spool to be wound thereon, a pressure applying member with yielding means to support it over and in contact with said spool, a pair of pressure applying members with means to support them yieldingly under and in operative contact with said spool, a single means including a lever and a weight to adjust the yielding pressure of the upper and lower pressure applying members on the spool as it is being wound, and means to shift each of said pressure applying members to inoperative position to permit access to or the removal of the spool.

25 30 35 40 45 50 55 60 65 70 75 80 85 90 95 100 105 110 115 120 125 130

21. In a pattern setting machine, means to detachably support and rotate a spool, means to guide a plurality of threads to said spool to be wound thereon, a pressure applying member with yielding means to support it over and in contact with said spool, a pair of pressure applying members with means to support them yieldingly under and in operative contact with said spool, a single means including a lever and a weight to adjust the yielding pressure of the upper and lower pressure applying members on the spool as it is being wound, and means to shift each of said pressure applying members to inoperative position to permit access to or the removal of the spool, said last named means comprising a cam, a cam shaft therefor, and a roller carried by said lever riding about the periphery of said cam for lowering the pair of lower pressure members.

25 30 35 40 45 50 55 60 65 70 75 80 85 90 95 100 105 110 115 120 125 130

21. In a pattern setting machine, means to detachably support and rotate a spool, means to guide a plurality of threads to said spool to be wound thereon, a pressure applying member with yielding means to support it over and in contact with said spool, a pair of pressure applying members with means to support them yieldingly under and in operative contact with said spool, a single means including a lever and a weight to adjust the yielding pressure of the upper and lower pressure applying members on the spool as it is being wound, and means to shift each of said pressure applying members to inoperative position to permit access to or the removal of the spool, said last named means comprising a peripheral cam, a slotted cam, a cam shaft therefor, a roller carried by said lever riding about the peripheral cam for lowering the pair of lower pressure members, and a roller carried by an arm secured to said lever riding in the slot of said slotted cam to shift the upper pressure member outwardly.

25 30 35 40 45 50 55 60 65 70 75 80 85 90 95 100 105 110 115 120 125 130

22. In a pattern setting machine, means to detachably support and rotate a spool, means to yieldingly support a pressure applying member above and in contact with said spool, means to yieldingly support a pressure applying member above and in contact with said spool, means to yieldingly support a pair of pressure applying members beneath and in contact with said spool, a lever, a weight carried by said lever, mechanism connecting

each of said pressure applying members to said lever, and means to shift each of said pressure applying members to inoperative position to permit access to or the removal of the spool, said last-named means comprising:
5 a peripheral cam, a slotted cam, a cam shaft therefor, a roller carried by said lever riding about the peripheral cam for lowering the pair of lower pressure members, and a roller carried by an arm secured to said lever riding
10 in the slot of said slotted cam to move the upper pressure member outwardly.

In testimony whereof I hereunto affix my signature.

GEORGE CROSSLAND.
